US0D1004558S

(12) **United States Design Patent** (10) Patent No.: **US D1,004,558 S**
(45) Date of Patent: ** Nov. 14, 2023

(54) **WIRELESS CONTROLLER**

(71) Applicant: **Lizhang Zhu**, Dongguan (CN)

(72) Inventor: **Lizhang Zhu**, Dongguan (CN)

(**) Term: **15 Years**

(21) Appl. No.: **29/880,747**

(22) Filed: **Jul. 27, 2023**

(30) **Foreign Application Priority Data**

Jul. 10, 2023 (EM) 015027361-0001

(51) **LOC (14) Cl.** **14-03**

(52) **U.S. Cl.**

USPC **D14/125**

(58) **Field of Classification Search**

(57) **CLAIM**

The ornamental design for a wireless controller, as shown and described.

DESCRIPTION

FIG. 1 is a front, right and top perspective view of a wireless controller, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
